UNITED STATES PATENT OFFICE.

JOHN W. VINCENT, OF KANSAS CITY, MISSOURI, ASSIGNOR TO VINCENT METAL WEATHERSTRIP COMPANY, A CORPORATION OF MISSOURI.

WEATHER-STRIP-FORMING MACHINE.

1,410,785.

Specification of Letters Patent. Patented Mar. 28, 1922.

Application filed March 26, 1920. Serial No. 368,922.

To all whom it may concern:

Be it known that I, JOHN W. VINCENT, a citizen of the United States, residing at Kansas City, in the county of Jackson and 5 State of Missouri, have invented certain new and useful Improvements in Weather-Strip-Forming Machines; and I do declare the following to be a full, clear, and exact description of the invention, such as will enable others skilled in the art to which it 10 appertains to make and use the same, reference being had to the accompanying drawings, and to the letters and figures of reference marked thereon, which form a part of 15 this specification.

This invention relates to a sheet metal working machine and particularly to means for cutting and crimping sheet metal in the form of weather strips in which the sheet is 20 formed with a crimped rib or abutment at right angles to the plane of the sheet.

The invention consists in providing certain novel parts and combinations of parts, all of which will be specifically referred to 25 hereinafter, reference being had to the accompanying drawings, in which—

Fig. I is a perspective view of a machine constructed in accordance with my invention, part of the feed table and sheet being broken away to show certain operating 30 mechanism therebeneath, and part of the crimping roller housing being broken away to show the operating mechanism for the crimping rollers.

Fig. II is a cross sectional view on the line II—II of Fig. I.

Fig. III is an enlarged elevational view of a pair of the rib-forming rollers.

Fig. IV is a similar view of a pair of the 40 rib-crimping rollers.

Fig. V is an elevational view of the sheet feed roller operating mechanism.

Fig. VI is a detail view of the finished weather strip, the product of the machine, 45 and

Fig. VII is a top plan view of a machine constructed in accordance with my invention.

In the illustrated embodiment of the invention I have shown a frame consisting of a table 1 supported upon standards or legs 2, 3, 4 and 5. Projecting upwardly from the table 1 are slotted standards 6 and 7, in which is a vertically movable reciproca- 50 tory knife, resting upon the expansion

springs 9 and 10 and engaged by the upper ends of the pitmen 11 and 12, which are connected to the cranks 13 and 14 on the rock shaft 15, mounted in bearings in the standards or legs 3 and 5. 60

The rock shaft 15 is provided with a crank arm 16, projecting inwardly to lie in the path of the roller or projection 17 on the rotating disk 18, rigid on the shaft 19 in bearings 20 and 21. The shaft 19 65 is rotated by a sprocket chain which passes around a sprocket 22 on shaft 19 and around a sprocket 23 on shaft 24, in bearings 25 and 26, supported from the standard 3 and table 1 respectively (see Fig. I). 70

The shaft 24 carries a pulley 27 driven by a belt 28 from the motor 29 on the bracket 30, carried by the machine frame. Therefore, when the motor is operating, the shaft 19 will be rotated, causing the roller or projection 17 to intermittently contact with the crank arm 16 to operate the knife 8 against the action of the springs 9 and 10 and after the roller or projection 17 has moved off the crank arm 16, the springs will raise the 80 knife 8 and, through the medium of the pitmen 11 and 12, the shaft 15 will be rocked so as to raise the arm 16 in a position to again be actuated by the projection or roller 17, when it reaches contacting position during each cycle of its operation. 85

Means is provided for feeding the sheet across the table so that the knife may shear it. The means illustrated consists of an idler roller 31, co-operating with a positively 90 driven roller receiving its motion from a pulley 33 on shaft 32. The pulley is driven through the medium of a belt 34, passing around the pulley 35 on shaft 24 and it is adapted to rotate the roller 36 to feed the sheet 37 toward the knife. When the knife has severed the sheet, it will drop into the trough-shaped guide 39 and be engaged by the rollers 42 and 43. Since the distance between the rollers 42 and 43 is slightly less 100 than the width of the severed strip, the strip will cup slightly and its edges will spring into the grooves 40 and 41 in the rollers 42 and 43 so that the rollers will guide and deliver it to the forming rolls. The roller 105 42 is driven from a shaft 44, having a gear 45 meshing with a gear 46 on shaft 24, so that the edges of the severed sheet will be frictionally engaged by the floors of the grooves 40 and 41 and be fed to the rib- 110

forming rollers, there being three sets of rollers illustrated in the drawings, said sets being designated by the reference numerals 47, 48 and 49. Each set consists of a bearing bracket 50 in which there is a top roller 51 on a shaft 52 in bearings 53 and 54, the circumferential groove 55 in each roller receiving a circumferential rib or flange 56 of a positively driven roller 57 on a shaft 58 in 10 bearings 59 and 60. The shaft 58 has, on one end, a beveled gear 61, meshing with a beveled gear 62 on the shaft 63, receiving its power from the spur gear 64 on the end of shaft 24 and which meshes with the gear 65 on the end of the shaft 63. Therefore, 15 when the shaft 24 rotates, the shaft 63 will rotate and through the medium of the gears, will drive the sets 47, 48 and 49 or rib-forming rollers.

20 In actual practice the ribs and grooves of the respective sets will be progressively diminished; that is, there will be a relatively wide rib and a relatively wide groove for the first set 47, and a relatively thin groove and 25 a correspondingly thin flange 56 for the succeeding sets of rollers so that the sheet or strip will be first formed into shape to provide the rib 66 for the strip 67 with the groove 68 relatively wide, but as the rib 66 progresses through the respective sets of 30 forming rollers 47, 48 and 49 the sides of the ribs will be drawn together until the grooves will be relatively narrow. Further 35 progression of the sheet 67 will move the rib between the crimping rollers in the housing 69 so that the sides of the rib 66 will be crimped together with the inner sides of the portions 70 and 71 not quite in intimate contact to afford a slight spring or give to the 40 rib 66.

The crimping rollers are shown as consisting of two pairs, one pair comprising a flanged idler roller 72 mounted in bearings in the housing 69 and a positively driven 45 flanged roller 73, also mounted in bearings in the housing on a shaft 74, the shaft 74 carrying a gear 75 meshing with an intermediate gear 76, which in turn meshes with a gear 77 on the shaft 78 of the flanged roller 50 79 of the second set, the flanged roller 79 having a complementary idler roller 80, also 55 mounted in the housing 69 and corresponding to the rollers 72. The gears 75 and 77 receive their motion from the gear 76, which is driven by a gear 81 on the shaft 63. The housing 69 is provided with a slot 82 through which the finished strip may pass onto the table 83.

The roller 36 is not continuously driven 60 but its shaft 36' carries a ratchet 84 adapted to be intermittently engaged by a pawl 85 on the lever 86, normally retracted by the spring 87, there also being a spring 88 between the lever and the pawl. The lever 65 86 extends radially from the shaft 36', on

which it is loosely mounted so that the projection 89 on the pulley 32 may intermittently contact with it and rotate the shaft 36 a sufficient distance to allow the sheet to feed one width of the strip to be formed into 70 the finished product during each cycle of operation so that the sheet is intermittently fed to the groove 39 as it is traversed longitudinally of the machine and while the feeding step is truly intermittent, the operation 75 is substantially continuous for as fast as the sheet is cut into strips, it is fed into the forming and crimping rollers to make the finished product.

The feed operating mechanism shown in 80 Fig. V will rotate the driven roller 36 to feed the sheet 37 a certain distance into the machine, the extent of the feed determining the width of the weather strip to be formed. Different widths of weather strips may be 85 made by changing the feed mechanism to govern the extent of movement of the sheet, as will be well understood.

From the foregoing it will be seen that as 90 the sheet is fed between the rollers 31 and 36 it will be cut, then fed longitudinally to the forming rollers and from the forming rollers to the crimping rollers, making the weather strip in the form shown in Fig. VI but with the sides 70 and 71 practically in 95 intimate contact.

What I claim and desire to secure by Letters-Patent is:

1. In a weather strip forming machine, 100 an intermittently operating feeding mechanism, an intermittently operating shearing mechanism in the path of the material fed by the feeding mechanism, a second feeding mechanism for feeding the sheared materials at right angles to the feed of the first mechanism, and rotary rib-forming dies in the path of travel of the material fed from the second mechanism.

2. In a weather strip forming machine, 110 an intermittently operating feeding mechanism, an intermittently operating shearing mechanism in the path of the material fed by the feeding mechanism, a second feeding mechanism for feeding the sheared materials at right angles to the feed of the first 115 mechanism, rotary rib-forming dies in the path of travel of the material fed from the second mechanism, and crimping means in line with the dies.

3. In a weather strip forming machine, 120 a frame, a shaft beneath the frame, means for driving said shaft, a feeding mechanism, means connecting the shaft and the feeding mechanism, a shearing means, shearing operating means, means connecting the shearing operating means and the shaft, a feeding means for feeding material at right angles to the feed of the first mechanism, means for driving the second feeding mechanism from the shaft, die rollers for fashion- 125 130

ing the material fed from the second feeding mechanism, gearing for driving said die rollers, and gear connections between the shaft and said gearing.

5. 4. In a weather strip forming machine, a frame, a shaft beneath the frame, means for driving said shaft, a feeding mechanism, means connecting the shaft and the feeding mechanism, a shearing means, shearing operating means, means connecting the shearing operating means and the shaft, a feeding means for feeding material at right angles to the feed of the first mechanism, means for driving the second feeding mechanism 10 from the shaft, die rollers for fashioning the material fed from the second feeding mechanism, gearing for driving said die rollers, gear connections between the shaft and said gearing, and crimping rollers 15 geared to synchronously operate with the die rollers.
5. In a weather strip forming machine, mechanical means for feeding a sheet of metal into the machine, means for shearing

the sheet into strips, sets of rib forming rollers at the end of the machine, and means for feeding the severed strips to the rib forming rollers.

6. In a weather strip forming machine, a frame, a shaft beneath the frame, means for driving said shaft, a feeding mechanism, means connecting the shaft and the feeding mechanism, a shearing means, shearing operating means, means connecting the shearing operating means and the shaft, a second feeding means, means for driving the second feeding means from the shaft, rib forming rollers and means for driving the rib forming rollers from the shaft.

7. In a weather strip forming machine, a sheet feeding means for progressively feeding the sheet into the machine, shearing means for shearing the sheet into strips, rib forming rollers, and means to feed the strips at right angles to the first feeding means to the rib forming rollers.

In testimony whereof I affix my signature.
JOHN W. VINCENT.
